BUCKLE

Morris Ruskin, Sea Point, Capetown, Cape Province, Union of South Africa

Application February 25, 1941, Serial No. 380,546
In the Union of South Africa May 3, 1940

6 Claims. (Cl. 24—206)

This invention relates to buckles (e. g. for fastening or tightening together the parts of garments) of the type in which the buckle frame is provided with a prong or other gripping device which is adapted to engage with or grip a strip of material passed through the frame.

The object of the present invention is to provide a buckle of this type which can be permanently concealed within the garment or other article with which it is used, and can nevertheless serve its purpose and be adjusted effectively and conveniently.

According to the invention, a buckle of the type stated is provided in which the strip to be engaged or gripped by the prong or other device is made of a rigid or springy character, or otherwise has sufficient rigidity to be pushed as a whole endwise, and the prong or gripping device itself is urged by spring means into gripping engagement with the strip, so that by merely pressing the gripping device against the action of the spring means and pushing together or easing apart the parts of the garment wherein the buckle is concealed, the strip will be caused to slide relatively to the buckle frame, and will be immediately re-engaged by the gripping device when the pressure thereon is relaxed.

Buckles embodying the invention will now be described by way of example with reference to the annexed drawing in which:

Figure 1 is a view in perspective of a buckle made according to the present invention.

Figure 2 is a view in perspective of a modified form of buckle embodying the invention; and

Figure 3 is a view in perspective of another modified form of buckle embodying the invention.

Referring to Fig. 1, the buckle frame 1 is adapted to be secured by stitching to one part of the garment (not shown), and the sliding strip 2 is adapted to be secured by stitching at its right-hand end to the other part of the garment, i. e. the part to be drawn more or less towards the part first mentioned. The strip 2 is made of spring steel with notches 3 along its length for engagement by the hook 4 of a spring grip 5 which is fixed in a clamp 6 formed integral with the buckle frame 1.

As will be apparent, the hook 4 can be disengaged from its notch 3 in the sliding strip 2 by merely pressing the spring grip 5 downwards. Thereupon the springy strip 2 can be slid relatively to the buckle frame 1, i. e. through the apertures 6 provided in the forwardly bent flanges 7 thereof. The user has no difficulty in operating the spring grip 5 and springy strip 2 by touch,

through the cloth or the like of the parts of the garment in which the buckle frame and strip are incorporated, and the appropriate notch 3 of the strip 2 will be immediately reengaged by the hook 4 when the pressure on the spring grip 5 is relaxed.

Referring to Fig. 2, in this case the buckle frame 8 is beaded over at its top and bottom edges so as to form sleeves 9 and 10 in which are secured the limbs of a U-shaped spring support 11. Upon this spring support, a laterally projecting prong 12 is provided. The frame 8 is formed with a central aperture 13, the prong 12 being in substantial alignment with the centre of this aperture. A spring steel strip 14 passes through the aperture 13 and in front of the U-shaped support 11 in such a manner that the strip passes behind the adjacent part 15 of the frame 8, which arrangement results in the springy strip 14 being under a constant pressure onto a prong 12.

In order to disengage the prong 12 from any of the holes 16 of the strip 14, the latter need only be pressed forwards away from the spring support 11, or the said support may be pressed backwards away from the strip. Thereupon the buckle frame 8 and strip 14 may be slid longitudinally in relation to each other to the extent required for the desired adjustment of the garment in which the buckle is incorporated.

Referring to Fig. 3, the buckle frame 17 is formed with a flange 18 which is provided with a slot 19 through which passes a spring steel strip 20. The frame 17 is formed at its other end with a sleeve 21 (which, for the sake of clearness, is shown partly broken away in the drawing). The bottom of the sleeve 21 is closed so as to accommodate a coiled spring 22, and the upper part of the sleeve 21 is occupied by a plunger 23. The sleeve 21 is formed with diametrically opposite slots 24 through which passes a spring steel strip 20, and the plunger 23, at the part 25 thereof adjacent to the strip 20, is made of semi-circular cross-section so as to pass up behind the strip, and thus not interfere with its lengthwise movement. At the junction of the part 25 (which is of semi-circular cross-section) and the lower part of the plunger 23 (which is of circular section), a landing 26 is formed, and this constitutes a tooth engageable with notches 27 formed on the lower edge of the strip 20.

As will be appreciated, the landing 26 can be disengaged from the notches 27 by merely depressing the plunger 23 against the action of the spring 22, whereupon the strip 20 can be moved lengthwise in relation to the buckle frame 17.

As in the case of the other buckles described, the grip upon the sliding strip is restored automatically by the spring means, after the wearer has adjusted the garment to his or her satisfaction.

As will be seen, the buckle constituting my invention can be readily made of a compact flat construction, all the parts lying in substantially the same plane. It can thus be entirely accommodated within a hem, waist-band, shoulder-strap, suspender, or the like.

The parts of the buckle may conveniently be made of metal, preferably of a non-rusting variety.

As applied to the waist-band of a pair of trousers, skirt or the like, buckles as above described serve to support the hips and keep the garment in a straight round position.

I claim:

1. A buckle for fastening together two relatively movable parts of an article and adapted to be concealed therein, comprising a rigid frame structure for one of said parts and having an opening therein, an elongated relatively flat strip of spring steel for the other of said parts having a series of openings spaced at intervals lengthwise thereof, said flat spring steel strip being arranged for lengthwise movement relative to said frame structure through the opening therein with the plane of the flat resilient strip disposed parallel and closely adjacent to the frame structure, and spring biased means carried by the frame structure operable normally to engage one of the openings in said spring steel strip thereby to secure the same against lengthwise movement with respect to the frame structure, said spring biased means being disengageable from the openings in the spring steel strip by effecting a relative separation thereof and said flat spring steel strip having sufficient rigidity crosswise the plane thereof to move lengthwise relative to said frame structure upon effecting a relative separation of the strip and said spring biased means.

2. A buckle for fastening together two relatively movable parts of an article and adapted to be concealed therein, comprising a rigid frame structure for one of said parts having an opening therein, an elongated relatively flat strip of spring steel for the other of said parts having a series of openings spaced at intervals lengthwise thereof, said flat spring steel strip being arranged for lengthwise movement relative to said frame structure through the opening therein with the plane of the flat resilient strip disposed parallel and closely adjacent the frame structure, and spring biased means on the frame structure disposed intermediate the latter and the spring steel strip and including a hook portion operable normally to engage one of the openings in said spring steel strip thereby to secure the same against lengthwise movement with respect to the frame structure, said spring biased means being disengageable from the openings in the spring steel strip by effecting a relative separation thereof and said flat spring steel strip having sufficient rigidity crosswise the plane thereof to move lengthwise relative to said frame structure upon effecting a relative separation of the strip and said spring biased means.

3. A buckle for fastening together two relatively movable parts of an article and adapted to be concealed therein, comprising a rigid frame structure for one of said parts having a flat body portion and flanges at its opposite ends

provided with aligned slots therein extending parallel to said frame structure body portion, an elongated relatively flat strip of spring steel for the other of said parts having a series of openings spaced at intervals lengthwise thereof, said flat spring steel strip being arranged for lengthwise movement relative to said frame structure through the slots in the end flanges thereof with the plane of the flat resilient strip disposed parallel and closely adjacent to the frame structure, and spring biased means carried by the frame structure operable normally to engage one of the openings in said spring steel strip thereby to secure the same against lengthwise movement with respect to the frame structure, said spring biased means being disengageable from the openings in the spring steel strip by effecting a relative separation thereof and said flat spring steel strip having sufficient rigidity crosswise the plane thereof to move lengthwise relative to said frame structure upon effecting a relative separation of the strip and said spring biased means.

4. A buckle for fastening together two relatively movable parts of an article and adapted to be concealed therein, comprising a rigid frame structure for one of said parts having a flat body portion and flanges at its opposite ends provided with aligned slots therein extending parallel to said frame structure body portion, an elongated relatively flat strip of spring steel for the other of said parts having a series of openings spaced at intervals lengthwise thereof, said flat spring steel strip being arranged for lengthwise movement relative to said frame structure through the slots in the end flanges thereof with the plane of the flat resilient strip disposed parallel and closely adjacent to the frame structure, and spring biased means on the frame structure disposed intermediate the latter and the spring steel strip and including a hook portion operable normally to engage one of the openings in said spring steel strip thereby to secure the same against lengthwise movement with respect to the frame structure, said spring biased means being disengageable from the openings in the spring steel strip by effecting a relative separation thereof and said flat spring steel strip having sufficient rigidity crosswise the plane thereof to move lengthwise relative to said frame structure upon effecting a relative separation of the strip and said spring biased means.

5. A buckle for fastening together two relatively movable parts of an article and adapted to be concealed therein, comprising a rigid frame structure for one of said parts, a flat body portion provided with an opening therein and having turned over edge portions along two opposite edges of said body portion, an elongated relatively flat strip of spring steel for the other of said parts having a series of openings spaced at intervals lengthwise thereof, said flat spring steel strip being arranged for lengthwise movement relative to said frame structure through the opening therein with the plane of the flat resilient strip disposed parallel and closely adjacent the frame structure, and spring biased means secured in the turned over edge portions of the frame structure and including a portion extending crosswise of the spring steel strip and provided with a projection, said means being operable normally to urge said projection into engagement with one of the openings in said steel strip thereby to secure the same against lengthwise movement with respect to the frame structure, said spring biased means being disengageable

from the openings in the spring steel strip by effecting a relative separation thereof and said flat spring steel strip having sufficient rigidity crosswise the plane thereof to move lengthwise relative to said frame structure upon effecting a relative separation of the strip and said spring biased means.

6. A buckle for fastening together two relatively movable parts of an article and adapted to be concealed therein, comprising a rigid frame structure for one of said parts having a flat body portion provided at one end with a flange having a slot therein and at the other end with a tubular sleeve portion having slots therein aligned with the slot in said flange, an elongated relatively flat strip of spring steel for the other of said parts having a series of openings spaced at intervals lengthwise along an edge thereof, said flat spring steel strip being arranged for lengthwise movement relative to said frame structure through 20

the slots in said flange and sleeve portions with the plane of the flat resilient strip disposed parallel and closely adjacent to the frame structure, a plunger element slidably mounted in the tubular sleeve portion and including a portion arranged for engagement with the openings in said spring steel strip, and spring means biasing said plunger in a direction normally urging said portion thereof into engagement with an opening in the strip thereby to secure the same against lengthwise movement relative to the frame structure, said plunger being disengageable from the openings in said strip by actuating the plunger against its spring bias to effect a relative separation of said plunger and strip, and said strip having sufficient rigidity crosswise the plane thereof to move lengthwise relative to the frame structure upon effecting a relative separation of the plunger and strip.

MORRIS RUSKIN.
